UNITED STATES PATENT OFFICE.

WILLIAM DENKMANN, OF WASHINGTON, DISTRICT OF COLUMBIA.

IMPROVEMENT IN AIR-ENGINES.

Specification forming part of Letters Patent No. 37,155, dated December 16, 1862.

To all whom it may concern:

Be it known that I, WILLIAM DENKMANN, of the city and county of Washington, District of Columbia, have invented a certain new and useful Improvement in Hot-Air or Caloric Engines; and I do hereby declare the following to be a full and exact description of the same, reference being had to the accompanying drawings, making part of this specification, in which—

Figure 1 is a plan or top view of a locomotive-engine, illustrating my invention. Fig. 2 is an end elevation of the same. Fig. 3 is a vertical longitudinal section at $x x$, Figs. 1 and 2. Fig. 4 is a vertical longitudinal section at $y y$. Fig. 5 is a perspective view of a portion of the machine on a larger scale. Fig. 6 is a vertical transverse section of the cam-wheels and yokes by which the valves are operated. Fig. 7 is a perspective view of the cam-wheel. Fig. 8 is a transverse section of the driving-cylinder at $z z$, Fig. 3. Figs. 9, 10, 11, and 12 are diagrams, showing the different positions of the cylinder-valves. Fig. 13 is an elevation illustrating another form or modification of the device for operating the said valves.

Similar letters of reference indicate corresponding parts in the several views.

The subject of my invention is a caloric-engine in which the air is heated in chambers separate from the driving-cylinder one stroke or more in advance of the time at which it is used, and at the instant required is applied in full force to the driving-piston.

The invention further consists in the use of an air-pump to supply the said heating-chamber with cold air.

To enable others skilled in the art to which my invention appertains to fully understand and use the same, I will proceed to describe its construction and operation.

A represents the bed or main frame of the engine, supported on two main driving-wheels, B B, and a steering-wheel, C, the latter journaled in the lower end of a vertical shaft, e, which may be rotated by a crank-shaft, D, and bevel-gears d, to turn the wheel in either direction and thus alter the course of the engine.

The drawings represent one side of the engine complete, which, as the two sides are in practice alike, will serve as an illustration for both. I therefore proceed to describe the side which is fully represented.

E represents a cog-wheel keyed upon the shaft a of the driving-wheels and receiving motion from a pinion, F, upon a crank shaft, G, when the said pinion is thrown into gear with its shaft by means of a clutch, H, operated by a lever, h. At other times the crank-shaft rotates within the pinion without communicating motion thereto. The crank-shaft receives its motion from a connecting-rod, I, attached to a cross-head, J, working upon a guide-rod, j, in customary manner, and driven by the piston k of the cylinder K. L represents an air pump cylinder, the piston or plunger l of which is driven, through the medium of a rod, m, by a lever, M, connected by a rod, m', to the cross-head J. l' l'' are valves opening inward to admit air into the cylinder L. The heating-chambers consist of two cylinders, each divided in the center, so as to constitute together four separate chambers, N' N² N³ N⁴, which are heated by furnaces O. 1 2 3 4 are pipes conveying air from the air-pump to the heating-chambers. 5 6 7 8 are pipes conveying air from the heating-chambers to the driving-cylinder K. 9 10 11 12 are exhaust-pipes from the driving cylinder. 13 14 15 16 are escape-pipes from the heating-chambers, which pipes are guarded by valves p and opened at proper times by levers P, actuated by tappets p' upon the shaft Q. r is a pinion upon the shaft G, meshing with a cog-wheel, R, upon a shaft or sleeve, S, which may work in line with the shaft Q, but (under the present illustration) must rotate at a speed double that of the latter. The shaft S carries four cam-wheels, S' S² S³ S⁴, each provided with one long projection, s', and two short projections, s'', the latter located on opposite sides of the periphery or ninety degrees on each side of the long projections s'. T' T² T³ T⁴ are yokes surrounded and actuated by the projections s' s² on the respective cam-wheels, the long projections s' acting to throw the yokes to the extremities of their stroke in either direction, and the short projections s² to hold them in an intermediate position. The said cam-wheels are so placed upon the shaft as to impart a successive motion to the various yokes in order to effect the required movement of the valves, as will be hereinafter explained. t' t² t³ t⁴ are rods communicating from the yokes to the valves U' U² U³ U⁴ of the driving-cylinder K. t⁵ t⁶ t⁷ t⁸ are rods communicating from the same

yokes to the valves of the air-pump L. V represents an aperture to which a smoke-pipe may be applied.

The operation is as follows: To start the engine, the air-pump must be operated by extraneous force to supply three of the four heating-chambers, N' N² N³ N⁴, with air, the fourth remaining empty. The engine is then ready for operation. The valves being placed in the position shown in Fig. 8, the pressure of heated air will be communicated from the chamber N' through the pipe 5 and port 5' to the front of the piston. At the same time the air in the rear of the piston k is permitted to escape through the port 9' and pipe 9. This action carries the pistons k and l to the positions shown in Fig. 3, the valve l' opening and admitting a supply of cold air to fill the pump-cylinder L in front of the piston l, while the air which was in the pump behind the piston l is forced through the pipe 1 into the heating-chamber N⁴. This position of the parts is shown in Figs. 3 and 9. The heated air within the chamber N' having done its work, the valves are moved to the position shown in Fig. 10, opening the exhaust-port 10' and hot-air port 6', while the other ports remain closed. At the same time the pipe 13 is opened instantaneously to permit the heated air within the chamber N' to escape. The pressure of air within the heating chamber N² is thus applied to the rear of the piston k, carrying the pistons k and l forward and forcing the air in the forward end of the air-pump into the heating-chamber N', when the pipe 14 is instantaneously opened to empty the chamber N². The valves are then moved by the cams to the position shown in Fig. 11, opening the ports 7'

11', by which the pressure from within the heating-chamber N³ is applied to the front of the piston k, the heating-chamber N² supplied with air from the air-pump, after which the chamber N³ is relieved of pressure. The valves are then placed in the position shown in Fig. 12, bringing the chamber N⁴ into action, supplying the chamber N², and again depleting the chamber N⁴. Then again in the position shown in Fig. 9, and so on in rotation.

It will thus be seen that by the simple expedient of using four heating-chambers the air is forced into the heating-chambers one stroke in advance of the time it is used, and so heated to a very high degree.

The cylinder and pump-valves may, if preferred, be attached to the same rods working transversely of the cylinders and operated by tappets, as shown in Fig. 13, or in any other suitable manner.

Having thus described my invention, what I claim as new therein, and desire to secure by Letters Patent, is—

1. The use of a plurality of separate heating-chambers operating successively in connection with each working end of the driving-cylinder K, substantially as set forth, to admit of heating the air in advance of the time at which it is used.

2. An air-pump, L, employed in combination with heating-chambers, substantially as set forth in the foregoing claim, to supply the said chambers successively with cold air.

WILLIAM DENKMANN.
